(57) CLAIM

We claim the ornamental design for a relaxation device, as shown and described.

DESCRIPTION

FIG. 1 is a perspective view of a relaxation device according to the present invention.

FIG. 2 is a front elevation view of the device shown in FIG. 1.

FIG. 3 is a rear elevation view of the device shown in FIG. 1.

FIG. 4 is a right elevation view of the device shown in FIG. 1.

FIG. 5 is a left elevation view of the device shown in FIG. 1; and,

FIG. 6 is a top plan view of the device shown in FIG. 1. The broken lines shown in the drawings are for the purpose of illustrating elements of the relaxation device that form no part of the claimed design.

1 Claim, 4 Drawing Sheets
